(No Model.)

J. DAY.

SUPPORT FOR CORNICE POLES.

No. 278,892.

Patented June 5, 1883.

UNITED STATES PATENT OFFICE.

JOHN DAY, OF BROOKLYN, NEW YORK.

SUPPORT FOR CORNICE-POLES.

SPECIFICATION forming part of Letters Patent No. 278,892, dated June 5, 1883.

Application filed April 23, 1883. (No model.)

To all whom it may concern:

Be it known that I, JOHN DAY, of Brooklyn, in the county of Kings and State of New York, have invented an Improvement in Supports for Cornice-Poles; and the following is declared to be a description of the same.

Before my invention stair-rods had frequently been provided with ornamental end pieces attached to the stair, and against which the 10 rod was held by an ornamental sliding band having lips to hold said rod in place, and stair-rods have also been made with an ornamental tubular end slotted to pass behind a screw-eye fastened in the stair, and said tubular end 15 was adapted to pass into or over the tubular stair-rod and hold the same in place.

My invention relates to devices for holding the cornice-pole in place; and it consists of a 20 segmental rest and sliding coupler. Said segmental rest is part of a cylinder upon which the pole rests at or near the end. The rest is formed as part of a bracket to be attached upon the outer facing of a window-casing; or it is provided with a metal back to be secured 25 upon the inner or opposite faces of a window or door casing or wall. The sliding coupler is slid upon the cornice-pole, and the latter is laid in the segmental rest, and the coupler slid along over the rest covering the same and se- 30 curing the rod in place.

In the drawings, Figure 1 is an elevation and partial section of a cornice-pole and bracket. Fig. 2 is an end view of the bracket. Fig. 3 is a perspective view of the segmental rest 35 as adapted for the opposite faces of a window or door casing. Fig. 4 is a perspective view of the sliding coupler, and Fig. 5 is a vertical section of the segmental rest and sliding coupler together.

40 In Fig. 1 the bracket *a* may be of any desired form or ornamentation. It is secured to the outer face of the window-casing in any convenient manner. The segmental rest *c* is secured to the side of the bracket. This form 45 in Fig. 1 is especially adapted to vestibule-door curtains. The same construction with a

different bracket is equally adapted for windows. This segmental rest *c* is a half-tube, and into it the cornice-pole *d* is laid.

The sliding coupler *e* may be made in any 50 ornamental form desired. It is a tube slightly larger in diameter than the cornice-pole *d*; or, in other words, it is large enough to slide over the pole and under the rest when the parts are put together. It may be plain, as shown in 55 Fig. 1, or cone-shaped with ribs, as shown in Figs. 4 and 5, in which latter case it binds against the segmental rest, and its spring action keeps it in place; or it may be held by a locking pin or screw to prevent the parts sepa- 60 rating.

To put the cornice-pole in place after the segmental rest has been secured to the window or door casing, it is only necessary to place the 65 sliding coupler over the end of the cornice-pole, to lay the end part of the cornice-pole in the segmental rest and slide the coupler back along the pole and over the rest to retain the parts in position.

The segmental rest *c* (shown in Fig. 3) is 70 made with a back plate, *f*, that is adapted to be fastened upon the opposite faces of a window or door casing by nails or screws.

I claim as my invention—

1. The combination, with the cornice-pole *d*, 75 of the bracket *a*, segmental rest *c*, and sliding coupler *e*, as and for the purposes set forth.

2. The combination, with a cornice-pole, of the segmental rest *c* and back plate, *f*, and the sliding coupler *e*, substantially as and for the 80 purposes set forth.

3. The segmental rest *c* and sliding coupler *e*, in combination with a cornice-pole, and means, substantially as described, for securing the segmental rest to a window or door casing, 85 as set forth.

Signed by me this 10th day of April, A. D. 1883.

JOHN DAY.
